UNITED STATES PATENT OFFICE.

EMIL K. F. STREICHERT, OF DETROIT, MICHIGAN.

RADIATOR.

1,189,507.

Specification of Letters Patent.

Patented July 4, 1916.

Application filed November 23, 1914. Serial No. 873,432.

To all whom it may concern:

Be it known that I, EMIL K. F. STREICHERT, a citizen of the United States of America, residing at Detroit, in the county of Wayne and State of Michigan, have invented certain new and useful Improvements in Radiators, of which the following is a specification, reference being had therein to the accompanying drawings.

10 This invention relates to radiators for water cooling devices for the circulating systems of automobiles or the like, and to an arrangement thereof whereby the joints are minimized, the disposition of the radiating surfaces to the air passages exposes maximum area of surface to the air while the construction as a whole is very firm and capable of resisting severe strains to which it is put in service on a rapidly moving car.

20 The invention consists in the matters hereinafter set forth, and more particularly pointed out in the appended claims.

In the drawings, Figure 1 is a front end elevation of a radiator that embodies features of the invention, the cellular construction thereof being shown diagrammatically; Fig. 2 is an enlarged view in vertical section through a portion of the cell structure of the radiator, parts being broken away; Fig. 3 is a view in transverse horizontal section through a portion of the cells of the radiator; Fig. 4 is an enlarged view in detail of the end face of a portion of the cellular body of the radiator, showing the offset margins of the component members; Fig. 5 is a view in detail of one of the rib plates, and Fig. 6 is a view in detail of one of the spacing plates.

Referring to the drawings, an upper 40 header 1 and lower header 2 with side members 3 are connected as a framework the body of which is filled with the cellular structure indicated generally at 4 that provides tortuous passages for circulating water or other cooling fluid from the upper header 1 to the lower header 2, interspersed with air cells or spaces extending from face to face of the body.

The cellular body is formed of pairs of 50 oppositely disposed rib plates 5 secured in spaced relation by the inset marginal portions 6 thereof that are firmly united as by brazing, soldering or welding to insure a tight joint. The rib plates are transversely 55 corrugated and at the alternate opposite

crests of these corrugations are folded on themselves to form spacing fins 7.

Pairs of corrugated spaced ribless plates 8 are secured by their offset margins 9 in spaced relation to form a tortuous or sinuous upright flattened conduit for the circulation of water or other cooling medium, the same being held in spaced relation to the contiguous pairs of rib plates 5 by the fins 7 thereof that extend into the angles of the 60 depressions or valleys in the plates. At the upper and lower ends of the conduits formed by the pairs of rib plates and pairs of spaced plates, the structure is completed by a flange 10 formed on either of the plates, 70 as the case may be, and infolded by the complementary members 11 of a lock seam flange formed on the contiguous member of either the spacing plate conduit or rib plate conduit. This insures a comparatively rigid 75 construction at the end of the conduit thereby stiffening the entire honeycomb body and providing convenient means for attaching the same to the upper and lower headers in the usual manner.

In assembling the plates to form the rib plate conduit, the position of the fins at the crests insures their alternation on opposite sides of the conduits and likewise insures a proper centering of this conduit in respect 85 to the other plate conduit adjacent to it. Because of the outfolding of the ribs from the conduits and the integral construction of the walls thereof there is no chance for leakage except at the union between the conduits and the headers and this is readily taken care of. Furthermore when assembled the honeycomb body may be readily 90 made tight by dip soldering or the like as the joints are entirely at the outer faces thereof and around the edges and the whole can be quickly and easily manufactured. It is extremely rigid because of the peculiar 95 bracing and centering effect of the ribs and this makes it especially desirable for use on 100 cars for heavy service where the vibrations might otherwise tend to disintegrate the body of the radiator.

Obviously, changes in the details of construction may be made without departing 105 from the spirit of my invention and I do not care to limit myself to any particular form or arrangement of parts.

What I claim is:—

1. A cooling honeycomb section for radi-

ators, the section being formed of pairs of plates that are transversely corrugated and are offset along the lateral margins thereof and secured together, the plates of one pair being folded on themselves at the crest of each corrugation to form spacing ribs and the other plates being correspondingly corrugated and bearing against the tips of the spacing ribs in the depressions of the corrugations of said plates, each pair of connected plates including a ribbed and ribless plate with the ribbed plates juxtaposed and the ribless plates similarly positioned.

2. A cooling honeycombed structure for radiators consisting of two adjacently positioned ribbed and transversely corrugated plates held in spaced relation by the inset marginal portions thereof with ribs projecting from alternate crests of the corrugations on opposite sides of the assembled pair, pairs of adjacently positioned ribless plates secured in spaced relation by the inset marginal portions thereof, the pairs of rib plates and spacing plates being disposed alternately with the ribs of the one resting in the depressions of the other, the end portions of adjacent plates of the several pairs being folded together to form flanges at the

points of connection with the upper and lower headers between which the pairs are disposed in substantially upright position.

3. A cellular cooling body structure consisting of tortuous upright ducts formed of transversely corrugated plates having ribs folded thereon to project laterally from the crests of said corrugations on opposite sides of the duct, the rear faces of the ribbed plates being adjacently positioned, and disposed alternately with conduits formed of transversely corrugated spaced ribless plates adjacently positioned, the ribs of the companion conduits bearing in the depressions of the conduits formed by the spaced plates, the plates of each pair constituting a conduit being held in spaced relation by inset marginal portions that are secured in abutting relation the conduits themselves being secured by companion flanges folded around each other from the adjacent plates of the conduits.

In testimony whereof I affix my signature in presence of two witnesses.

EMIL K. F. STREICHERT.
